with the carriage support, constitutes the case shift frame on which the carriage is supported for bodily movement therewith fore and aft of the machine. The forward 5 end of each plate 37 is pivoted, as at 38, to a depending link 39, pivoted at its upper end on a pivot pin 40 that projects inwardly from the associated side plate 2 of the frame. In this manner the case shift frame is supported at its forward end by the parallel 10 links 39 and is supported at its rear end by the parallel arms 34.

Not only is the carriage shiftable with the case shift frame, but among other devices 15 that are also shiftable with said frame are the feed rack 41, the margin and line lock stops 42, the dog rocker 43, the universal bar 44, the frame 45 to which the universal bar is connected, the ribbon vibrator 46, its actuating arm 46^a, the ribbon spools 47, the ribbon feed mechanism including the ratchet wheel 48, the ribbon feed pawl 49, its actuating arm 50, the actuating arm 51 for the dog rocker, the rack 52 for the back spacer, 20 and the back spacer actuating rod 53.

The case shift frame may be shifted by any suitable means, those shown comprising a shifting lever 54 to which a link 55 is connected. The upper end of said link is pivoted to a bell crank lever 56, pivoted at 57 (see Fig. 4) on a stud projecting from the left-hand side plate 2 of the frame, and held in place thereon by a screw 58. A depending arm 59 on its bell crank lever co-acts 30 with the projection on the shift frame to shift it rearwardly to the upper case position. The parts may be locked in shifted position by a shift lock key 60 that controls a shift lock member 60^a mounted on the 35 front of the comb plate 6.

The space key 61 has its supporting levers 61^a fulcrumed on the comb plate 6 and extending rearwardly and down therefrom and connecting at their lower ends with a 40 squared cross bar 62. This bar carries an arm 63 operatively connected with a link 64 pivoted at its lower end to an actuating arm which forms part of the dog rocker.

It will be seen, therefore, that every working 50 part of the machine is carried by the inner frame, and that the construction is such that all of said parts may be assembled, mounted in place, and adjusted in said frame while it is detached from the outer frame. 55 The inner frame with the parts mounted thereon may then be introduced into the outer frame as a single unit without dismantling any part of the machine, and without having had occasion to handle or mar the 60 outer frame until the inner frame with the working parts thereon, is to be placed in position therein and the machine as a whole is ready to be delivered as a finished product.

The outer frame is preferably made of 65 thin sheet metal such as steel and is very

light since the strain on the machine is borne in the main by the inner frame. The main purpose of the outer frame is to cover many of the working parts and the unfinished inner frame, and impart to the machine a finished appearance and outline. Although the outer frame is light in weight, it adds, nevertheless, as a strengthening factor to the machine as a whole when secured in place with the top plate added. These parts tend to 70 strengthen and render more rigid the inner frame, and the machine as a whole, as will hereinafter appear. The outer frame, which is shown in detail in Fig. 1 and designated as a whole by the reference numeral 65, is made of two separate members welded together along the base at both sides and at the front, to form in effect one part. The lower member is formed from a single piece of metal of rectangular formation, as viewed 75 from above, with an inwardly directed flange 66 joined to an upwardly extending surrounding wall 67. Each front, back and side wall of this member is therefore angular, or substantially L-shaped in cross section. The 80 inwardly extending flange 66 is apertured at its four corners to receive rubber feet 68, as fully disclosed in the hereinbefore mentioned application Sr. No. 469,458, and by 85 which the machine is supported on its base-board. The other member of the frame section is formed from a continuous piece of sheet metal with a front cross piece or wall 69 and side walls 70. The body portion of 90 each side wall has a rearwardly extending portion 70^a near its lower edge corresponding substantially to the projections 21 on the inner frame and, like the latter, forming an L-shaped or angular recess through which the carriage may travel. Beginning at the 95 top edge 70^b, and at or about the point where the comb plate 6 of the inner frame is situated when the parts are assembled, each side plate 70 slopes downwardly and forwardly 100 at 71 to the front wall 69. An integral, inwardly turned flange, beading or rib 72 is formed on each inclined edge and continues 105 along the upper edge of the wall 69. This flange gives a finish to the frame and strengthens and renders it more rigid. In 110 order that the side walls of the outer frame may bear against the outer sides of the plates 2 of the inner frame at the points where the two frames are secured together, I prefer to form integral, inwardly extending bearing lugs 73 and 74 on the side walls 115 70 and 67, respectively, of the outer frame members, thus maintaining the side-walls of the inner and outer frame sections spaced apart except at the points where they are 120 rigidly connected together, as indicated in Fig. 2.

The flange 66, where it extends across the machine at the front thereof, carries a sheet metal bracket 75, fixed thereto at 76. This 125 130

UNITED STATES PATENT OFFICE.

DAVID E. G. CLARKE, OF BAYONNE, NEW JERSEY.

WATER-TUBE BOILER.

Application filed March 13, 1918. Serial No. 222,073.

To all whom it may concern:

Be it known that I, DAVID E. G. CLARKE, of Bayonne, in the county of Hudson and in the State of New Jersey, have invented 5 a certain new and useful Improvement in a Water-Tube Boiler, and do hereby declare that the following is a full, clear, and exact description thereof.

My invention relates to a water tube boiler 10 and has for its object to provide a steam generating apparatus constructed of standardized units adapted to be assembled to produce any desired horsepower and which is characterized by simplicity of construction and ease of erection.

A further object of my invention is to provide a steam generating apparatus constructed of assembled units the number of which can be increased without increasing 20 materially the diameter of the steam and water drum.

A further object of my invention is to provide a steam generating apparatus which requires a minimum amount of head room.

25 A further object of my invention is to provide a steam generating apparatus in which the tubes are easy of access for replacement and cleaning.

Other and further objects of my invention 30 will be apparent from the following description of one embodiment thereof as illustrated in the accompanying drawings, in which—

Figure 1 is a view partly in front elevation and partly in section;

Figure 2 a section on line 2—2 of Figure 1 looking in the direction of the arrows; and

Figures 3 and 4 views similar to the right-hand portion of Figure 1 and illustrating 40 modifications.

Similar reference characters refer to similar parts throughout the drawings.

The embodiment of my invention chosen for purposes of illustration is of the type 45 illustrated in United States Letters Patent to Morrin No. 950,296 granted February 22, 1910, for a steam boiler and in United States Letters Patent to Hoxie No. 1,102,407 granted July 7, 1914, for a water tube boiler.

50 It will be understood, however, that the invention is not limited to the type of apparatus disclosed by these patents. Thus, the invention may be embodied in a single bank or banks of units, or in any other desired

type of steam producing apparatus, instead of in the inverted V construction type illustrated.

It will be noted that to increase the horsepower of the apparatus illustrated in the above-mentioned patents, it is necessary to increase the diameter of the steam and water drum in order to accommodate the necessary additional tubes. Such structures, therefore, practically have to be made to order as standardization of parts is difficult if not impossible. In my invention, the parts can be standardized, made and kept in stock, and a steam producing apparatus of any desired horsepower readily and quickly constructed by assembling any desired number of units or sections. The diameter of the steam and water drum need not be changed for apparatus developing different horsepower, as it is necessary only to add to the depth, number, or other dimensions of the tube units, as may be most convenient. The parts are simple in construction. The headers, for example, have straight sides and may be standardized and kept in stock. The diameter of the tubes likewise may be standardized and kept in stock. When a boiler is desired, it is necessary only to cut the tubes the desired length and expand them in the headers, or the complete sections or units may be made up 70 and kept ready for assembling.

Referring to the drawings, a unit or section consists of an upper header indicated by reference character 1, a lower header 2, and tubes 3 which are expanded or otherwise inserted in the headers. The tubes may be either curved or straight. The headers preferably are longitudinally extending boxes with straight sides and substantially square in cross section. The shape and dimensions 95 may be varied if desired. Any desired number of units or sections may be assembled to give any required horsepower. The water and steam drum 5 preferably runs substantially at right angles to the headers, which are connected to the drum in any desired manner as by nipples 4. With this construction it is not necessary for the steam and water drum to be entirely above the headers, or of the top of the tubes as is the case in the patents referred to above, thus saving head room. A similar result may be obtained by suitable connections even though 100 105

the steam and water drum runs parallel with the headers, but the form illustrated is a convenient and space-economizing type. A down comer or circulating tube 6 connects drum 5 with bottom header 2. A mud drum 7 with blow valve 8 may be provided for removing sediment from bottom headers 2, the drum being connected therewith in any desired manner as by nipples 9.

10 It is preferable to have baffles 10 to insure a thorough circulation of the hot gases among the tubes. Hand holes 11 are provided in upper headers 1 and hand holes 12 in lower headers 2 in order to provide easy 15 access to the tube ends.

A suitable steam offtake pipe may be provided in the apparatus such as that indicated by the element 13.

Figures 3 and 4 represent modifications. 20 Figure 3 illustrates a modification in which the sections or units are all of the same length, but the headers all are in the same plane instead of in parallel planes as illustrated in Figure 1. In this construction the 25 means connecting the upper headers with the water and steam drum 5 will vary in length as illustrated by the varying lengths of nipples 4. In Figure 4, the lower headers are all in the same plane, but the sections 30 vary in length so that the center of each upper header is at the same height with respect to the water and steam drum.

Many modifications of my invention will be apparent to those skilled in the art, my 35 invention not being limited to the particular embodiment thereof chosen for purposes of illustration, but consisting of a water tube boiler made in sections adapted to be stand- ardedized for rapid assembling.

What I claim is:

1. In a steam generating system, a water 40 circulating system for the generation of steam comprising a horizontal, elongated drum adapted to be filled partly with water when in use, a plurality of horizontal, upper 45 headers extending at right angles to said drum with one end of each header adjacent the side of said drum and connected therewith below the water level of said drum and with the series of ends extending side by 50 side along said drum, a plurality of horizontal, lower headers spaced apart from and below and corresponding in number to said upper headers but so arranged that straight lines drawn between corresponding upper 55 and lower headers will form a series of inverted V's to provide a space for the heating medium, downcomers connected to said drum below its water level and to said lower headers, and a plurality of tubes connecting 60 corresponding upper and lower headers to form therewith a complete separable unit, whereby the heating medium will pass from the inverted V formed by said tubes through said tubes and heat the water therein so that 65 it will circulate from said tubes through their upper headers, the drum, the down- comers, the lower headers, and again into the tubes.

2. The structure specified in claim 1 in 70 which baffles are interposed between the tubes to cause the heating medium to follow a tortuous passage therethrough whereby the heating medium is utilized with great efficiency.

In testimony that I claim the foregoing I have hereunto set hand.

DAVID E. G. CLARKE.
